(57) CLAIM

I claim the ornamental design for an elliptical cycle, as shown and described.

DESCRIPTION

FIG. 1 is a top perspective view of an elliptical cycle; FIG. 2 is a bottom perspective view of the elliptical cycle in FIG. 1; FIG. 3 is a rear elevation view of the elliptical cycle in FIG. 1; FIG. 4 is a front elevation view of the elliptical cycle in FIG. 1; FIG. 5 is a first side elevation view of the elliptical cycle in FIG. 1; FIG. 6 is a second side elevation view of the elliptical cycle in FIG. 1; FIG. 7 is a top plan view of the elliptical cycle in FIG. 1; and, FIG. 8 is a bottom plan view of the elliptical cycle in FIG. 1.

The broken lines are included for the purpose of illustrating the unclaimed portions of the article and form no part of the claim.

1 Claim, 8 Drawing Sheets
